UNITED STATES PATENT OFFICE

2,406,943

MEANS FOR FORMING CORRUGATED TUBE
FROM A STRIPShirley J. Carter, Hayward, Calif., assignor to
Titeflex, Inc., a corporation of New Jersey

Application August 18, 1943, Serial No. 499,085

11 Claims. (Cl. 113—35)

1

This invention relates to corrugated tube formed from a strip wherein is a central longitudinal fold or groove and the edges of the adjacent convolutions are interfolded to secure them together. Such a tube is shown in the United States patent to L. H. Brinkman, No. 1,198,392, patented September 12, 1916.

Tubes of the character as described in the Brinkman patent referred to have been formed by apparatus involving the drawing of the corrugations through a stationary die. This causes considerable friction in the die which reduces the efficiency of operation and also tends to wear the die whereby its accuracy is impaired and this may extend, within a comparatively short time, to the point where the die, or some part of it, cannot be used further. This wearing of the die causes inaccuracy in the formation of the tube which may even cause imperfections and lack of tightness in the interfolded joint. Moreover, the die is difficult and expensive to maintain and manufacture.

It is the main object of the present invention to provide apparatus for forming a tube of the character described which shall avoid the disadvantages referred to, which shall be efficient in operation, which shall accurately and reliably form the tube including its interfolded joint, which shall be of long life and shall be relatively easy and inexpensive to manufacture and maintain.

A further object of the invention is to provide an improved method for forming the corrugated tube whereby the advantages as referred to may be realized and the disadvantages, as also referred to, may be avoided.

Other and ancillary objects of the invention will appear hereinafter.

In the accompanying drawings which illustrate the invention—

Fig. 1 is a top plan view of apparatus embodying the invention of means and by which the invention of method may be practiced;

Fig. 2 is a side elevation of the apparatus of Fig. 1;

Fig. 3 is a top plan view, partly broken away, of a fragment of the pre-forming means for shaping the cross section of the strip prior to its entry into the tube-forming mechanism, showing the manner of mounting and adjusting two adjacent strip forming rollers for movement toward and away from their companion rollers and the means for effecting such movement;

Fig. 4 is an enlarged sectional view, broken away, through the first pair of rollers for ini-

2

tially forming the cross section of the strip before its entry into the tube-forming mechanism;

Fig. 5 is a cross section, broken away and to the same scale as Fig. 4, through the second pair of strip cross section forming rollers showing a further forming of the strip cross section;

Fig. 6 is a view similar and to the same scale as Figs. 4 and 5 showing the third pair of strip cross section forming rollers at which the strip is given its final cross sectional shape before entering the tube-forming apparatus;

Fig. 7 is a top plan view, on an enlarged scale, of the mechanism for helically coiling the strip and seaming it into the tube, partly broken away to show a fragmentary section, the forming and stripping rollers being in open or inoperative position to permit adjustment or inspection of the strip;

Fig. 8 is a top plan view of the apparatus of Fig. 7 to the same scale as Fig. 7 but with the stripper and sealing rolls in closed, that is, operative, position;

Fig. 9 is a section on the line 9—9 of Fig. 7;

Fig. 10 is an enlargement of the upper end of Fig. 9 to show a fragmentary section, the forming and stripping rollers being in open or inoperative position;

Fig. 11 is a section on the line 11—11 of Fig. 7;

Fig. 12 is a section on the line 12—12 of Fig. 9;

Fig. 13 is a section on the line 13—13 of Fig. 9;

Fig. 14 is a section on the line 14—14 of Fig. 11;

Fig. 15 is a section on the line 15—15 of Fig. 11;

Fig. 16 is a fragmentary section, on an enlarged scale, on the line 16—16 of Fig. 8;

Fig. 17 is a section, on an enlarged scale, and partly broken away, on the line 17—17 of Fig. 8;

Fig. 18 is a fragmentary section on the line 18—18 of Fig. 17 and to the same scale as Fig. 17;

Fig. 19 is a section on the line 19—19 of Fig. 18, on an enlarged scale and partly broken away showing the initial stage of the interfolding or seaming of the edges of adjacent convolutions of the strip;

Fig. 20 is a section on the line 20—20 of Fig. 18 to the same scale as Fig. 19 and showing the strip in the later and completed stages of interfolding of the edges of adjacent convolutions of the strip, seaming them together;

Fig. 21 is a fragmentary side elevation, partly in section and partly broken away, indicating the relations of the sealing and stripper rolls to each other and to the tube and adjacent parts;

Fig. 22 is a fragmentary view showing in section, on an enlarged scale, a portion of the tube as produced by the apparatus referred to; and

55 Figs. 23 to 25 are views indicating diagram-

matically the manner of interfolding the strip edges to seam them together.

Referring to the drawings, the apparatus comprises a strip forming device whereby the flat strip or ribbon of metal from which the tube is to be formed, is made of the requisite cross section for entry into the machine whereby the strip is helically coiled and the edges of the adjacent convolutions are interfolded to form the tube.

The flat metal strip 1 (see Figs. 1 to 6) drawn from a reel or other suitable source of supply, passes about a pulley 2 rotatably mounted in the stationary support 3, whence the strip passes about a pulley 4, also rotatably mounted on the stationary support 3, but having its axis at substantially right angles to that of the pulley 2.

The flat strip thence passes about the strip forming roller 5 and between the roller 5 and its cooperating roller 6. Both of the rollers 5 and 6 are rotatably mounted and when in forming position have the cooperating faces and form the flat strip into a cross section as shown in Fig. 4. The strip with cross section as shown in Fig. 4, then passes between the rotatably mounted forming rollers 7 and 8 which, when in forming relationship, have the cooperating faces and form a cross section of strip as shown in Fig. 5. The strip with cross section as shown in Fig. 5 then passes on between the rotatable forming rollers 9 and 10 which, when in forming position, have cooperating forming faces and shape the strip into a cross section as shown in Fig. 6.

The cross section of the strip, as it leaves the rollers 9 and 10, is suitable for forming into the tube, and the strip passes from the rollers 9 and 10 into the tube forming machine as will be hereinafter referred to.

The rollers 5, 7, and 9 are rotatably mounted in the stationary support 3. The rollers 6, 8, and 10, however, are so mounted as to be capable of movement away from the rollers 5, 7, and 9 respectively to permit placing of the strip in position, to adjust or inspect the strip, or for other reasons, and of being moved into forming relationship with the rollers 5, 7, and 9 respectively to form the proper cross section of strip. Thus (see Fig. 3) each of the rollers 6, 8, and 10 is similarly mounted so that a description of the mounting of one will apply to each; thus the roller 6 is rotatably mounted on a pin 11 fixed in a block 12 rocking about a pivot 13 in a recess of the support 3. In the block 12 is a recess 14 into which extends a reciprocating plunger 15 having an anti-friction roll 16 at its end. The plunger 15 reciprocates in a cylindrical handle 17 and has a shoulder 18 between which and the end of the cylindrical handle is interposed a spring 19 tending to force the plunger outwardly. The cylindrical handle 17 is pivoted to the frame 3 at 20 and the plunger is maintained in proper angular position about its axis by a pin 21 secured to the plunger and sliding in a slot 22 in the end of the handle 17. The handle 17 having been turned about its pivot 20 into the position as shown, the line of action of the plunger on the block will be to the right of the pivot 13 and the end of the block carrying the roller will tend to be forced by the spring 19 to turn about its pivot 13 in a clockwise direction. In this position of the block the roller will be 70 pressed toward its companion roller by the pressure of the spring 19 so that the strip will be formed of the desired cross section for that stage. It will be observed that in this position the roller carried by the block 12 is spring-pressed

75 toward its companion roller so that the proper pressure upon the strip between the rollers will be maintained at all times, the spring insuring such pressure even though the parts may become worn or mal-adjusted to some extent.

It having been observed that the line of pressure of the plunger upon the block 12 to force its carried roller toward its companion roller, is to the right (Fig. 3) of the block pivot 13, if now 10 it be desired to move the roller carried by the block 12 away from its companion roller, the handle 17 is thrown to the right of its position in Fig. 3 until the line of action of the plunger 15 upon the block 12 is to the left of the pivot 13. The block then will be turned quickly by the pressure of the spring 19 to remove its carried roller outwardly away from cooperation with its companion roller and the rollers will be separated for inserting, inspecting or adjusting the strip 15 as before referred to.

It will further be observed that the block 12 and the plunger 15, in conjunction with the pivot 13, provide a toggle for operating the roller carried by the block, such roller being quickly 20 snapped into inoperative or open position as the roller 16 passes to the left of the pivot 13, and is positively held in that position, while the roller is snapped into and positively held in its operative or closed relation to its companion roller, when 25 the roller 16 passes to the right of the pivot 13.

It will now appear that the rollers 6, 8, and 10, are opened up or removed from operative, that is strip forming, relation with their companion rollers 5, 7, and 9 by throwing their respective handles 17 to the left (see Figs. 1 and 3). The strip having been placed in position, the handles 17 are thrown to the right (Figs. 1 and 3) when the rollers 6, 8, and 10 are thrown into cooperative relationship with the rollers 5, 7, and 9 (see 30 Figs. 4, 5, and 6) to form the desired cross section of the strip. The strip is drawn through the apparatus just described, by the pull upon it of the tube forming mechanism which is power driven as will hereinafter appear. The metal strip delivered from the rollers 9 and 10 (see Fig. 6) then passes to the tube forming machine which will now be described. It will be observed that the strip as it leaves the rollers 9 and 10, has the longitudinal, central fold or groove 100', the sides of which form the corrugation sides, and the marginal portion of the strip on one side of the groove has the transverse, right angled bend 101'; while the marginal portion on the other side of the groove is transversely bent to form the curled over portion comprising the inclined part 102 having the hook 103 at its outer extremity. As will hereinafter appear, the strip is, in the machine through which it subsequently passes, helically coiled, the curled over edge at one side of one convolution embraces the outer radial portion of the right angled edge 101' of the adjacent convolution and the engaged edges are folded inwardly to seam the adjacent convolutions together.

The tube forming machine comprises a head including the end pieces 20 and 21 encircled and spaced apart, so as to form a space 22 between them, by a cylinder 23, the whole being clamped together by means of screws 24. Also a cover plate 25 is secured to the end piece 20 by means of screws 26. The space 22 may be filled with oil whence it will lubricate the parts contained therein and proceed to the various bearings connected therewith.

The central shaft 27 driven by any suitable

source of power, as for instance an electric motor, is rotatably mounted in the end piece 21 and has fixed to it a central coupling member 28 having projecting from it the fingers or studs 29 which enter loosely between the projecting fingers 30 on the coupling member 31 whereby a universal coupling of well known construction is provided. The coupling member 32 is rotatably mounted in the end piece 20 by means of the ball bearing 33.

Coaxial with the shaft 27 and fixed to the member 32 is a shaft 34 journaled in the member 35 mounted and fixed in the end piece 20. The shaft 34 is fixed to the member 32 by a flat plate 32' clamped against a flattened side of the shaft 24 and a flattened side of the member 32 by screws 33 passing through the plate and screwed into the member 32. At its upper end the shaft 34 has fixed upon it the mandrel 36 upon which the formed tube is delivered by the stripping rolls after the edges of the adjacent convolutions of the helically disposed strip have been interfolded together by the sealing roll and its cooperating reaction roll upon the interior of the tube as will be hereinafter referred to.

Rotatably mounted on the member 35 is the sleeve 37 to which is integrally fixed the reaction roller 38 and a gear 39. The reaction roller is formed by forming the annular grooves 38' and 39' in the member 37 whereby the annular ridges 40' and 41' and the annular shoulder 42' are formed. It will be observed that the axis of the reaction roller is inclined to the axis of the mandrel. This gives the inclination of the reaction roller necessary to conform to the pitch of the strip as helically disposed to form the tube.

Surrounding the member 37 and clamped in place against the interior of the end piece 20 by the cover plate 25, is a housing 44 for the reaction roller and its driving gear 39, this housing being split on the diameter 43' to permit assembly of the parts within it. The housing has a central, annular, raised portion 45 about the central hole, such raised portion having on its outside the helical surfaces 71 and 72 corresponding to the pitch of the strip as helically disposed in the tube, for supporting and guiding the lower right-angle shaped edge of the strip firmly and surely into proper position to be embraced by the curled over edge of the incoming strip. Upon its inner side the member 44 has an inwardly extending annular projection 73 and also an arc-shaped, inwardly extending projection 74, the projection 74 fitting within the groove 39' and the annular projection 73 fitting into the groove 38', the fit being a close running fit so that the annular ridges 40' and 41' and the whole reaction roller are firmly held in position.

The annular, raised part 45 is coaxial with the mandrel 36 and the shaft 34, and the diameter of the upper part of the portion 45 is substantially the same as the diameter of the innermost part of the formed corrugated tube 75, so that the tube slips readily from the portion 45 to the adjacent portion of the mandrel 36, which mandrel portion is of substantially the same diameter. The portion of the mandrel which is adjacent to the portion 45 therefore holds the formed tube in line adjacent to the region of the formation of the tube so that the parts are held in place, but thereafter the mandrel beyond the shoulder 76 may be of smaller diameter, its one function being to prevent the formed tube from falling too far out of line, and the friction between the tube and the mandrel is decreased.

The reaction roller is, it will be observed, (see

particularly Figs. 17 and 18), eccentric with relation to the shaft 34 and the raised portion 45 so that the ridges of the reaction roller extend outside the circumference of the part 45 so as to cooperate with the sealing roller 47 to perform the interlocking or seaming together of the edges of adjacent convolutions as will be hereinafter referred to.

To drive the reaction roller the gear 39 meshes with a gear 40 fixed upon a shaft 41 rotatably mounted in the end piece 20 and having fixed upon it the gear 42 which meshes with the gear 43 fixed upon the member 32 so that the reaction roller is driven from the power shaft 27. It will be observed that the shaft 41 is inclined to the axis of the mandrel and is substantially parallel to the axis of the reaction roller. This arrangement of gearing and shafts enables the reaction roller to be driven on its axis at an angle to the mandrel axis, from the power shaft 27 which is coaxial with the mandrel.

Distributed about the center of the shaft 27 and approximately 120° apart are the stripper rolls 45' and 46 and the sealing roll 47. The sealing roll 47 cooperates with the reaction roller 38 to interfold the adjacent edges of the incoming strip and its preceding convolution, thereby sealing the edges of the incoming strip to its preceding convolution in the tube, while the stripper rollers 45' and 46 engage the tube to hold the parts in position and force the tube or "strip" it out upon and along the mandrel 36 whence it issues from the machine as the completed tube. The rolls 45', 46 and 47 are inclined to the axis of the mandrel and of the tube being formed, the shafts carrying these rollers being mounted upon shafts inclined to the mandrel and tube axis so that the rolls may properly conform to the helical contour of the strip forming tube. Also the rolls 45', 46 and 47 are mounted so as to be movable toward and away from the mandrel axis so as to be movable into position to operate upon the strip and tube or into inoperative position where the strip and tube under the rollers may be inspected or adjusted. The mountings for the rollers 45', 46 and 47 are similar and consequently a description of the mounting for one of such rollers will apply to each and the mounting of the stripper roll 46 has been chosen for the purpose of illustrating this mounting (see Fig. 11).

The stripper roll 46 is fixed upon a shaft 48 rotatably mounted in the sleeve 49 fixed to an arm or block 50 rotatably mounted upon a shaft 51 which is mounted in the end piece 20. Rotating upon the shaft 51 is a gear 52 meshing with the gear 53 fixed upon the shaft 48. The roller 46 may be moved into and out of operative position (toward and away from the mandrel axis) by rocking the sleeve 49 about the center of the shaft 51, the end piece 20 having a recess 54 to accommodate the sleeve 49 and the support 50 and permit the rocking movement thereof as referred to. It will be seen that the rocking movement of the sleeve 49 about the shaft 51 will also be about the axis of the gear 52, so that the gears 53 and 52 will stay in mesh regardless of the swinging or rocking motion of the sleeve 49, the shafts 51 and 48 being parallel.

The gear 52 is a part of the sleeve 55 rotatably mounted upon the shaft 51 and comprising the integrally formed universal coupling member 56 having a series of projections 57 entering loosely in between the projections 58 of another coupling member. This form of universal coupling is well

known and requires no further description. The coupling member 58 is rotatably mounted upon a stud 59 fixed in the piece 21 and has fixed to it the gear 60. This gear being driven through the train of gearing comprising the gear 61 fixed upon the central drive shaft 27 which meshes with the gear 62 fixed to the gear 63; the gears 62 and 63 being rotatably mounted upon the stud 64 fixed in the end head 21. The gear 63 meshes with the gear 65 rotatably mounted upon the stud 66 for the sealing roller 47, the stud 66 corresponding to the stud 59 for the stripper roll 46. The gear 65 meshes with the idler gear 67 rotatably mounted on the end head 21, the gear 67 in turn meshing with the gear 68 rotatably mounted upon the stud 69 for the stripper roll 45, such stud corresponding to the stud 59 for the roll 46. The gear 68 meshes with the idler gear 70 rotatably mounted in the end head 21, the gear 70 meshing with the gear 60 secured to the universal coupling member 58 driving the shaft 48 for the stripper roll 46.

The shafts 80 and 81 upon which the stripper roll 45 and the sealing roll 47 are respectively fixed, respectively correspond with the shaft 48 of the stripper roll 46. Upon these shafts 80 and 81 are respectively fixed the gears 82 and 83 which respectively mesh with the gears 84 and 85 upon the sleeves 86 and 87 corresponding respectively with the sleeve 55 in relation to the stripper roll 46, the sleeves 86 and 87 being respectively rotatably mounted on shafts 88 and 89 corresponding respectively to the shaft 51 of roll 46 and driven through universal coupling by means of gears 88 and 89 in a manner as set forth in connection with stripper roll 46.

The arm or block 50 pivoted on the shaft 51 is acted upon by a spring-pressed plunger 90 having an anti-friction roller at its end and extending into the recess 91 in the block 50. The plunger 90 reciprocates endwise in a cylinder 92 pivoted in the end head 20 and pressed outwardly of the cylinder towards the block by means of a spring. This construction is similar to the block and operating means of the rollers 5, 7, and 9 (see Fig. 3). In the case of the shaft 48, this, with its stripping roller, is moved outwardly or is pressed inwardly according to which side of the center of the shaft 51 the line of pressure of the plunger 90 is on. An adjustable stop screw 93 in the block 50 comes against the head 20 to limit the inward movement of the roll on the shaft 48.

It will be seen (Fig. 14) that the same construction of means is employed for swinging the shaft 81 of the re-action roller 47 about the shaft 89 and the shaft 80 of the stripper roller 45 about the shaft 88. Details of the operating means for thus swinging the shafts of the rollers respectively are shown for example in connection with the shaft 81 of the sealing roll 47, the spring pressed toggle block 93 being shifted by the plunger 94 sliding in the cylinder 95 and pressed outwardly by a spring 95 interposed between a shoulder on the plunger and the end of the cylinder (see Fig. 7) and the cylinder 95 being pivoted to the end piece 20 at 97. To hold the plunger in proper angular position a pin 98 extending through the plunger sides in a slot 99 in the end of the plunger. In order to close the recess in which the block 93 is located, a circular wall 100 is tightly secured to the block 20 and a flexible diaphragm 101, such as leather or rubber, is secured in a fluid-tight manner to the rim of the wall 100 and also to the plunger 95. This effectually closes off the recess from the ex-

terior and prevents the passage in either direction of oil, water or dust, and at the same time permits the handle 95 to be rocked in either direction about its pivot 97 to swing the shaft 81 about the shaft 89 as before referred to. It will be seen that a similar mechanism is provided for swinging the shaft 80 about the shaft 88.

The sealing roller 47 has the annular corrugations or ridges 105 and 106 between which is an annular groove into which the ridge 41' of the reaction roller extends, the ridges 105 and 106 respectively extending into the grooves 39' and 38'. The ridges 105 and 106 extend into the central longitudinal groove, in the incoming strip and in the preceding adjacent convolution. As the strip is drawn into the apparatus, the curled edge of the incoming strip embraces the radial edge of the last preceding convolution shortly before the strip edges pass between the sealing and reaction rollers. The two edges as so engaged are drawn into the groove in the sealing roller, between the ridge 41' of the reaction roller and the bottom of the groove, radial pressure being gradually applied to them whereby they are pressed together and interfolded until at the point of nearest approach of the rollers the edges will be tightly interfolded and pressed together. This is especially shown in Figs. 18, 19, and 20. The curled over edge, comprising the parts 102 and 103, of the incoming strip embraces the radial edge 101' of the last convolution seamed into the tube, just before the rollers are reached. As the rollers are more closely approached, the interengaging edges occupy a position as shown in Fig. 19 and then, as they are drawn further in between the rollers, they are further folded over into the position as shown in section in Fig. 20, and on being drawn between the rollers to the point of their closest approach the interengaging strip edges will be pressed into their final, compact interfolded position as shown in 107 (Fig. 20) and as in the completed tube see 108 (Fig. 22).

The operation of interfolding the strip edges may be further explained with reference to Figs. 23 to 25. Referring to Fig. 23, the dotted line 101' represents a transverse section of the radial edge of a strip convolution already seamed into the tube at its other edge, while the dotted line comprising the parts 103, 102 and 100' represents a transverse section of the incoming strip. It will have been observed that the incoming strip is in a line substantially tangential to the reaction and sealing rollers while the radial edge 101' of the convolution already seamed to the tube at its other edge, moves in a circle about the mandrel axis and that as the said edge 101' rotates and the incoming strip is drawn in between the reaction and sealing rollers 38 and 47, the said edge 101' and the curled edge of the incoming strip will converge, the edge 101' passing gradually within the embrace of the curled over edge of the incoming strip and the two edges being gradually bent over together by the application of radial pressure until in the position of nearest approach of the rollers the edges are interfolded into the completed seam.

In Fig. 23 the marginal portions of the strip sections represented by the dotted lines are those which will be interfolded together, occupying the same position longitudinally of the completed seam. In the position shown in Fig. 23, these sections of the strip edges have not progressed far enough toward the rollers to have the radial edge 101' enter within the curled edge of the incoming strip although it is about to do so. As these strip

sections approach the complete interfolded position between the rollers as referred to, they will reach a position as indicated in Fig. 24 where the edge 101' has entered within the curled over edge of the incoming strip and both have been bent laterally of the seam, the portion 101' having its edge cammed outwardly by and sliding along the inclined part 102 toward the hook 103. As these sections move further toward the full interfolded position the edge of the portion 101' will move into the hook 103 and the parts will finally be bent into the full interfolded position as shown in Fig. 25 at the point of nearest approach of the rollers. Succeeding sections will be acted upon in a similar manner and thus the seaming of the incoming strip to the edge of the last preceding convolution secured at its other edge into the tube, will be carried on continuously for as long a period as is desired. It will be observed that this interfolding is accomplished by radial pressure upon the interengaging strip edges, such pressure being exerted on the peak 109 of the curled over portion of the incoming strip thereby bending the inclined portion 102 about its end 110. As the part 102 is thus bent, the radial edge of the adjacent convolution will be bent with it into the final interfolded condition in the completed seam. The inclination of the part 102 will facilitate and insure the proper movement of the radial strip edge which is embraced by the curled over portion, so that the two strip edges are certainly and accurately moved into the final interfolded condition as referred to. From the reaction and sealing rollers the seam passes into the annular groove 111 of the stripper roller 45' and thence about the portion 45 to the groove 112 in the stripper roller 46. The seam thus passes on in the completed tube and out upon the mandrel.

The stripper rollers 45' and 46 are alike, the roller 45' being displaced from the sealing roller by one third of the pitch of the seam in the completed tube, along the tube axis, and, the roller 46 being displaced from the roller 45' by one third of the seam pitch, along the tube axis whereby the seam in passing through the grooves of the stripping rollers as referred to, conforms to the helix of the corrugation in the completed tube. As shown, there are other annular grooves than those mentioned in the stripper rollers whereby ridges on those rollers are adapted to engage in the helical groove of the tube already formed thereby improving their engagement with the tube. The sealing, reaction and stripping rollers being driven in the directions as indicated by the arrows in Fig. 18, the tube will be rotated in a counter-clockwise direction (Fig. 18) and, its corrugation engaging in the grooves of the sealing and stripper rollers arranged axially of the tube so as to conform to the pitch thereof, will cause the tube to move outwardly upon and along the mandrel and thence pass from the mechanism. The mandrel is driven in the direction of rotation of the tube but, in order to avoid all danger of snubbing of the tube thereon it is driven at a slightly slower speed than the tube.

The operation of the mechanism may be briefly traced as follows:

The strip from which the tube is made is formed by a series of pairs of rollers so as to be of the proper cross section for introduction into the mechanism for helically disposing it and interfolding the edges of adjacent convolutions. This strip is drawn through the preforming rolls and into the seaming and coiling mechanism by the rotation of the tube already formed by reason

of the driven stripper rollers and also the grip of the driven reaction and sealing rollers on the incoming strip and the tube convolution with which it is interfolded.

The incoming strip proceeds from the rolls so that its right angled edge rests upon the helical supporting surfaces 71 and 72, the plane of the strip preforming rolls being preferably inclined (see Fig. 2) to correspond to the helical pitch of the surfaces 71 and 72. The incoming strip is thus positioned with relation to the convolution to which it is to be seamed, so that the curled over edge of the strip embraces or hooks over the radial edge of the convolution. The two edges thus interengaged, then are drawn in between the reaction and sealing rollers whereby they are gradually bent over into final interfolded condition by the radial pressure of the sealing roller thereon. The interfolded or seamed edges then pass on through the helically arranged stripper rollers by which the tube is moved longitudinally onto the mandrel as before described.

It will be seen that the incoming strip is continuously seamed to the next preceding convolution so long as it is desired to continue the operation and that such strip is bent into its helical form by being seamed to the convolution.

The drive shaft 27 may be driven by an electric motor 110 supplied with current from mains 111, the operation of the motor being controlled by a main switch 112.

In the apparatus illustrated provision is made for soldering the seam. This is accomplished by drawing into the seam as it is formed, a thread 113 of solder which may have a flux incorporated with it as is well understood. Such solder thread being incorporated in the seam, is drawn thereby from a reel 114 over the idler pulleys 115 and 115'. The tube, complete except for heating and subsequent cooling to accomplish the soldering operation as is well understood, with the solder thread in the seam, is as shown in Fig. 22. The tube of Fig. 22 is then heated to effect the soldering of the point and is then allowed to cool.

It is desirable, where soldering is wanted, that if the solder thread should break the operation of the machine should stop in order to avoid unsoldered portions of the seam. To this end a switch is provided in the supply circuit of the motor having a pivoted member 116 carrying one of the switch contacts, biased to separate its carried contact from the other switch contact and open the circuit. The pivoted member, however, carries a roller 117 over which the solder thread 114 passes and the tension on the thread occasioned by the drawing of the thread into the seam from the reel, holds the contacts together and maintains the motor circuit. Should the thread break, its tension would be removed and the arm 116 would move to separate the contacts thereby stopping the motor.

If it is not desired to solder the seam, the solder thread may be omitted from the seam, the operation of forcing the tube from the strip being as hereinbefore described. Also where the solder thread is omitted the thread reel, its idler guide pulleys and the solder thread controlled switch in the motor circuit, should be omitted, the last mentioned switch being substituted by a permanent circuit connection.

While the invention has been illustrated in what are considered its best applications, the invention of apparatus may be embodied in other structures and the invention of method may be variously practised without departing from its

11

spirit. The invention of apparatus is not therefore limited to the structures of the drawings and the method is not limited to the precise details recited.

What I claim is:

1. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, and a rotatable sealing roller, said sealing and reaction rollers having cooperating grooves and ridges adapted to interfold marginal portions of the strip.

2. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, and a rotatable sealing roller, said sealing and reaction rollers having cooperating grooves and ridges adapted to interfold marginal portions of the strip and a stripper roller engaging said strip after it has been secured to the tube, for urging the tube longitudinally.

3. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, and a rotatable sealing roller, said sealing and reaction rollers having cooperating grooves and ridges adapted to interfold marginal portions of the strip and a plurality of stripper rollers engaging said strip after it has been secured to the tube, for urging the tube longitudinally, said sealing and stripper rollers being symmetrically placed about said member.

4. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, a rotatable sealing roller, said sealing and reaction rollers having cooperating grooves and ridges adapted to interfold marginal portions of the strip and a rotatable mandrel substantially coaxial with said member.

5. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, a rotatable sealing roller, said sealing and reaction rollers having cooperating grooves and ridges adapted to interfold marginal portions of the strip and a rotatable mandrel substantially coaxial with said member, said mandrel adjacent said member being of substantially the same diameter as said member and of less diameter at a distance from said member.

6. A mechanism for forming a corrugated tube from a strip comprising in combination a mem-

12

ber about which the strip passes, a rotatable reaction roller embraced by said member, said roller being eccentric with relation to said member and said member having an opening at one side permitting cooperation of said reaction roller with a sealing roller, a rotatable sealing roller, said sealing and reaction rollers having cooperating grooves and ridges adapted to interfold marginal portions of the strip and a helical support for the strip extending about said member.

5 7. A mechanism for forming a corrugated tube from a strip comprising, in combination a member about which the strip passes, a rotatable reaction roller embraced by said member, said roller being eccentric with relation to said member and said member having an opening at one side permitting cooperation of said reaction roller with a sealing roller, a rotatable sealing roller, said sealing and reaction rollers having cooperating grooves and ridges adapted to interfold marginal portions of the strip, said sealing roller being mounted to move toward and away from said reaction roller.

15 8. A mechanism for forming a corrugated tube from a strip comprising in combination a member about which the strip passes, a rotatable reaction roller embraced by said member, said roller being eccentric with relation to said member and said member having an opening at one side permitting cooperation of said reaction roller with a sealing roller, a rotatable sealing roller, said sealing and reaction rollers having cooperating grooves and ridges adapted to interfold marginal portions of the strip, a stripper roller engaging said strip after it has been secured to the tube, for urging the tube longitudinally, and means for spring pressing said sealing and stripper rollers toward the axis of said member.

25 9. In a mechanism for forming corrugated tubing from a strip which is helically disposed and has edges of adjacent convolutions interfolded, in combination, a mandrel coaxial with and internal of the formed tube, a reaction roller adjacent one end of the mandrel having annular grooves and ridges and extending within the formed tube, an external sealing roller having annular grooves and ridges cooperating with the reaction roller to interfold the edges of adjacent convolutions of the strip, and means to rotate the mandrel, said rotating means being situated remotely of said mandrel and said reaction roller and including a drive shaft passing through said reaction roller and connected with said mandrel.

30 10. In a mechanism for forming corrugated tubing from a strip which is helically disposed and has edges of adjacent convolutions interfolded, in combination, a cylindrical mandrel coaxial with and internal of the formed tube, said mandrel having an outside diameter substantially equal to the inside diameter of the formed tube, a reaction roller adjacent one end of said mandrel having annular grooves and ridges and extending partly within the tube formed, the outside diameter of the portion so extending being smaller than the outside diameter of the mandrel, an external sealing roller having annular grooves and ridges cooperating with the reaction roller to interfold the edges of adjacent convolutions of the strip, and means to rotate the mandrel, said rotating means being situated remotely of said mandrel and said reaction roller and including a drive shaft passing through said reaction roller and connected with said mandrel.

35 11. In a mechanism for forming corrugated tubing in a strip which is helically disposed and

13

has edges of adjacent convolutions interfolded, in combination, a mandrel coaxial with and internal of the formed tube, a reaction roller adjacent one end of the mandrel having annular grooves and ridges and extending within the formed tube, said reaction roller being arranged for rotation about an axis which is angularly disposed with respect to the longitudinal axis of the mandrel, an external sealing roller having an

14

annular grooves and ridges cooperating with the reaction roller to interfold the edges of adjacent convolutions of the strip, and means to rotate the mandrel, said rotating means being situated remotely of said mandrel and said reaction roller and including a drive shaft passing through said reaction roller and connected with said mandrel.

SHIRLEY J. CARTER.
